UNITED STATES PATENT OFFICE.

CHARLES A. SAWTELLE, OF DAYTON, OHIO.

INTERNAL-COMBUSTION ENGINE.

1,201,507.

Specification of Letters Patent. Patented Oct. 17, 1916.

Application filed October 17, 1912. Serial No. 726,197.

To all whom it may concern:

Be it known that I, CHARLES A. SAWTELLE, a citizen of the United States, residing at Dayton, in the county of Montgomery and State of Ohio, have invented 5 certain new and useful Improvements in Internal-Combustion Engines, of which the following is a specification, reference being had therein to the accompanying drawing.

10 This invention relates to internal combustion engines and more particularly to engines of the two cycle type.

The primary object of the invention is to provide means to quickly and efficiently exhaust the burnt gases from the cylinder 15 and introduce a fresh mixture therein.

To this end it is a further object to provide the cylinder with a large exhaust port near the lower limit of the stroke of the piston; to provide means to inject the fresh 20 mixture into the cylinder at a point above the exhaust port; and to cause the inlet port to be opened and closed within the brief interval during which the edge of the piston 25 is below the exhaust port.

Another object of the invention is to provide means whereby a light charge of the explosive mixture may be introduced into the cylinder and prevented from mingling 30 with the burnt gases before it is ignited, thereby enabling the engine to be throttled to a low speed.

Other objects of the invention are to admit the explosive mixture through the 35 piston; to provide a large exhaust port; to introduce the explosive mixture into the crank-case through the shaft bearing and to adequately control the introduction thereof; and to so construct and organize 40 the engine as a whole as to provide a simple, positively operated mechanism which will permit the movements of the parts to be properly timed.

In the accompanying drawings, Figure 1 45 is a vertical, sectional view, taken through the crank casing and one cylinder of an engine embodying my invention; Figs. 2, 3 and 4 are detail views taken through the cylinder showing the several parts of the 50 mechanism in successive positions; Fig. 5 is a section taken on the line $\alpha\alpha$ of Fig. 1; and Fig. 6 is a section taken through the intake bearing of the shaft.

In these drawings I have illustrated one 55 embodiment of my invention and have shown the same as comprising a cylinder 1,

of the water jacket type, mounted upon a base 2 and having an inclosed crank casing 3 into which the explosive mixture is drawn and compressed in the usual manner, 60 although it will be understood that the compression of the mixture may be secured in any suitable manner. Mounted within the crank casing is the usual crank shaft 4 having a wrist pin 5 on which is mounted a connecting rod 6, the upper end of which is connected with the piston 7 which is mounted within the cylinder 1 and is of the trunk-piston type. As is usual in two cycle engines the exhaustion of the burnt gases 70 from the cylinder takes place during the lower portion of the power stroke of the piston and the fresh explosive mixture is introduced into the cylinder under pressure and thus serves to not only charge the 75 cylinder for another explosion but to assist in scavenging the cylinder, that is, forcing out the burnt gases. In the present instance, however, I have so arranged the parts that this is effected in a very efficient 80 manner. To accomplish this the fresh mixture is introduced through the main piston 7 and the exhaust port 8 is arranged near the lower limit of the stroke of the main piston. By introducing the gas through the 85 main piston I am enabled to employ a very large exhaust port and I cause the same to extend substantially about the entire circumference of the cylinder. The fresh mixture is introduced through a central pas- 90 sageway or supplemental cylinder 9 formed in the main piston 7, preferably by securing the upper end of the supplemental cylinder within a central opening in the piston head, thus leaving both the inner and outer 95 walls of the supplemental cylinder clear for the operation of the controlling parts, as hereinafter described. In order that the 100 fresh mixture may be introduced at a point above the exhaust passage I have made the piston of such a length that its extreme upper end will lie at a point above the plane of the exhaust port when the piston is in its lowermost position and have then cut away or beveled the edges of the piston, as 105 indicated at 10, to connect the exhaust port with the main cylinder when the main piston is in its lower position. In this manner I am, as above stated, enabled to place a large exhaust port near the lower limit of 110 the stroke of the main piston and thus utilize the full power of the explosion and fur-

ther, when the piston has moved downward a distance sufficient to cause the side walls thereof to clear the exhaust port the burnt gases will exhaust quickly through the port and the fresh mixture will be introduced into the central part of the cylinder at a point above the exhaust port. This mixture being introduced under pressure will pass upward through the central part of the cylinder and coming in contact with the cylinder head will be deflected and caused to move downward along the side walls of the cylinder, thus forcing the burnt gases down and through the exhaust port. The action is such that there is very little tendency on the part of the fresh mixture to mingle with the burnt gases. This action takes place while the main or power piston is at substantially the lowermost limit of its stroke and as this piston moves upward to again close the exhaust port the burnt gases will be further expelled from the cylinder, thus making the exhaustion of the burnt gases very complete.

25 The admission of the fresh mixture through the supplemental cylinder 9 may be accomplished and controlled in any suitable manner. In the present instance I have shown the supplemental cylinder as having inlet ports 11, there being several shown in the present drawings, but the number being optional. It will be noted that when these ports are open they will connect the supplemental cylinder with the interior of the main piston which is in open communication with the compression crank case. Consequently, the compressed mixture in the crank case will pass through the ports, through the supplemental cylinder 9 into the main cylinder 1. The cylinder may be provided with devices of any suitable kind to control the inlet ports. In the present construction I have utilized a supplemental piston 12 which is mounted within the supplemental cylinder and is adapted to move across the inlet port or ports to close them and to be moved downwardly a distance sufficient to clear these ports and connect the crank case with the main cylinder. Co-operating with the supplemental piston is a slidable member 13 which is here shown in the form of a sleeve mounted on the exterior of the supplemental cylinder and having movement relatively to this cylinder and to the supplemental piston, the relative movements of the supplemental piston and the sleeve serving to control the admission of the compressed mixture through the ports 11 of the supplemental cylinder, the sleeve being in the present instance provided with ports 14 which may be moved into and out of alinement with the ports 11. The movements of the supplemental piston and its co-operating sleeve are so timed that the inlet port 11 of the supplemental cylinder will be

opened after the upper edge of the side wall of the main piston has cleared the exhaust port 8 and will be closed at the very beginning of the upward stroke of the piston. These movements are preferably controlled by suitable connections with the crank shaft and these connections are such that a very short movement of the crank while it is in its inner or lowermost position, where it imparts a minimum of movement to the piston, will first open and then close the inlet ports. The supplemental piston 12 is preferably actuated by a connecting rod 15 having at its lower end an eccentric strap 16 mounted on an eccentric 17 rigidly secured to the wrist pin 5 of the crank shaft. The arrangement of this eccentric relative to the crank shaft is such as to cause the movements of the supplemental piston to bear a proper relation to the movements of the main piston. The co-operating part or sleeve 13 is here shown as actuated from the crank shaft through a connection with the connecting rod 6 for the main piston. An arm 18 is pivotally connected at its upper end with the sleeve 13 and at its lower end with one arm 19 of a bell crank lever mounted on a stud 20 carried by the lower portion of the main piston 7. The other arm of the bell crank lever extends upwardly, as shown at 21, and has secured thereto a link 22 which is pivotally connected at its opposite end to the connecting rod 6. Obviously, the movement of the connecting rod 6 will cause the bell crank lever 19-21 to move about its axis, thereby imparting vertical movement to the sleeve. The arrangement of the parts is such as to properly time the movement of the sleeve with relation to the main piston and the supplemental piston. There may be one or more of the arms, 18, preferably there is one on each side of the supplemental cylinder and they lie between the connecting rod 6 for the main piston and the side walls of this piston. The connecting rods and their co-operating parts may be of any suitable construction. Those here shown were designed to provide the necessary clearance. It will be noted that the connecting rod 6 is in two parts, joined near their upper ends by a transverse bar 6^a (only one part of the rod being here shown), and the connecting rod 15, for the supplemental, piston, is arranged between the two parts of the connecting rod 6, while the arms 18 are offset to clear the latter rod and are connected by a cross piece 18^a.

It will be apparent that the operation of the crank shaft and the main piston will impart movement to the supplemental piston and the sleeve 13. This movement is such that when the main piston is in its outermost position, that is, the position which it occupies when the explosion takes place, the supplemental piston will be in

its outermost position and will extend across the inner ends of the inlet ports. Thus the supplemental piston becomes a part of the main piston and receives a portion of the 5 force of the explosion. Inasmuch as this piston extends across the inlet ports the sleeve is not subjected to any portion of the force of the explosion. Fig. 1 of the drawings shows the parts in this position, the 10 main piston being there shown as just beginning its inward movement. As the main piston moves inward the supplemental piston and the sleeve move inward therewith, but the movements of the supplemental piston 15 and sleeve relatively to the supplemental cylinder are such that the inlet port will be closed by the outward movement of the sleeve before the supplemental piston has been moved beyond the outer edge of said 20 port. The parts are shown in this position in Fig. 2, these being the positions occupied by the parts just prior to the opening of the exhaust port. The further inward movement of the main piston opens the 25 exhaust port and immediately thereafter opens the inlet port. The position of the parts will be noted in Fig. 3 in which the main piston is shown as having just cleared the exhaust port and the inlet port is shown as 30 wide open, thus permitting the free entrance of the compressed mixture into the main cylinder. The main piston is here shown as in substantially its innermost position and as the crank shaft swings across 35 its center to begin the outward movement there is very little movement on the part of the main piston but this action of the crank shaft causes the sleeve 13 to move inward and close the inlet port. It will be 40 noted that the inlet port is closed very quickly, the movement of the sleeve being accomplished by a very short movement of the crank shaft and this movement of the crank shaft being during that portion of 45 its revolution when its movement has little effect upon the main piston.

It will be noted that when the parts are in the position shown in Fig. 4 the inlet ports are closed and the supplemental piston 50 is in the lower portion of the supplemental cylinder; thus affording additional space within the main cylinder to receive the explosive mixture. As the main piston moves outward the supplemental piston not 55 only moves outward therewith but moves outward relatively thereto, thereby accomplishing an additional compression of the mixture in the main cylinder.

Heretofore much difficulty has been experienced in throttling down a two cycle engine, this being due in large part to the tendency of the fresh mixture to mingle with the burnt gases in the cylinder. If 60 only a small charge of the fresh mixture was 65 introduced into the cylinder there would

remain a proportionately large amount of burnt gases with which the fresh mixture would mingle, thus very materially reducing, if not entirely destroying, its explosive qualities. It will be noted that in the 70 present engine the supplemental cylinder forms a pocket through which the fresh mixture must pass to enter the main cylinder. When a small charge of the fresh mixture is introduced into the cylinder a 75 large part of it will remain in the supplemental cylinder or pocket and will be compressed therein, thus preventing its mingling to any material extent with the burnt gases in the main cylinder. By a suitable 80 arrangement of the spark plug this charge can be ignited within the supplemental cylinder and thus the full explosive force of the mixture utilized. In this manner the desired amount of fresh mixture can be in- 85 troduced into the engine and it can be throttled down to the desired extent. The spark plug may be arranged in any manner which will enable the spark to ignite the fresh mixture within the supplemental cyl- 90 95 inder when the upper portion of the main cylinder contains burnt gases. In the form of the engine here shown the spark plug is mounted centrally in the head of the main cylinder and projects downward to such an extent that the spark will be formed within or very close to the lower end of the supplemental cylinder.

It will be noted that the arrangement of the supplemental piston within the supplemental cylinder is such that this supplemental piston receives the force of the explosion and further that it closes the inlet ports and thus prevents the force of the explosion passing through these ports and 100 coming in contact with the sleeve on the outer side of the supplemental cylinder. In this manner the sleeve is protected from injury and the supplemental piston is caused to form a part of the main piston and to 110 receive its proportionate share of the force of the explosion. The supplemental piston and the main piston are connected to the crank shaft by the same wrist pin, as indicated at 5, and thus the force of the explo- 115 sion will be exerted squarely upon the crank shaft and will be utilized to the fullest extent.

As has been stated the explosive mixture may be introduced into the crank case and 120 compressed in any suitable manner. I prefer, however, to introduce the same through one of the bearings for the crank shaft and to control the admission of the mixture by the movement of this shaft.

In Fig. 6 of the drawings I have illustrated a construction of bearing and shaft by means of which this may be accomplished and which will afford a very adequate and very accurate control for the admission of the 130

21 mixture. The bearing here illustrated is designed for use with a two cylinder engine and is adapted to be placed between the two cylinders with the crank shaft 4 projecting 5 on either side thereof to the respective crank-cases. The bearing is indicated at 24 and has in one side thereof a port 25 which communicates with a source of supply for the explosive mixture, such as the carbureter. The 10 shaft 4 is provided on each side thereof with a radial port 26, each of which is adapted to be moved into alignment with the port 25 of the bearing once during each revolution of the shaft 4. These radial ports communicate 15 with longitudinal passages 27 formed in the shaft 4, extending beyond the ends of the bearings and communicating with the interiors of the respective crank-cases. The arrangement of the ports 26 in the shaft is such 20 that the inlet port 25 will be in communication with the crank-case of each cylinder during the outward movement of the piston for that cylinder. Thus, the piston will serve to draw into the crank case a quantity of explosive mixture and the return or inward 25 movement of the piston will serve to compress this mixture in the crank-case.

To prevent leakage of the mixture about the bearing I have provided a special packing which is very efficient. That portion of the engine shaft 4 which extends through the bearing is provided near its ends with annular flanges 28 which extend beyond the brass or other material 29 which forms the bearing 30 surface for the bearing and fits snugly within the metal shell or body portion of the bearing 24, the brass 29 being slightly shorter than the shell of the bearing so as to form recesses to receive these flanges. At each end of the 35 bearing an annular recess 30 is formed between the brass and the shell of the bearing and in each recess is mounted a ring 31, preferably of metal, which fits snugly against the corresponding flange 28, the engaging surfaces being ground if desired. A second ring 32 is mounted in each recess 30 and between the two rings is a ring of compressible packing 33. Means are provided for exerting a pressure on the ring 32 which will not only 40 force the outer ring 31 into engagement with the corresponding flange on the shaft, but will also compress the packing ring and cause the inner and outer peripheries of these rings to bear tightly against the brass and 45 shell of the bearing, respectively. The pressure on each ring 32 is preferably secured by means of a series of coiled springs 34 which are interposed between the corresponding spring and a fixed part of the bearing which 50 is here shown as a portion 35 extending inwardly from the shell of the bearing.

While I have shown and described one embodiment of the invention it will be understood that this has been chosen for the purposes of illustration only and that I do not 55

desire to be limited to the details of construction shown and described, for obvious modifications will occur to a person skilled in the art.

Having thus fully described my invention, 70 what I claim as new and desire to secure by Letters Patent, is:—

1. In an engine, a main cylinder communicating with an exhaust passage, a closed crank case communicating with a source of 75 gas supply, a main piston, a supplemental cylinder carried by said main piston and communicating with said main cylinder and with the crank case, and means to control the communication between said supplemental 80 cylinder and said crank case.

2. In an engine, a main cylinder communicating with an exhaust passage, a closed crank case communicating with a source of 85 gas supply, a main piston, a supplemental cylinder carried by said main piston and communicating with said main cylinder and with said crank case, and means comprising a supplemental piston to control the communication between said supplemental cylinder 90 and said crank case.

3. In an engine, a main cylinder communicating with an exhaust passage, a main piston, a supplemental cylinder carried by said main piston and communicating with said 95 main cylinder and with a source of fluid supply, a supplemental piston mounted in said supplemental cylinder, and a part coöperating with said supplemental piston to control the communication between said supplemental 100 cylinder and said source of supply.

4. In an engine, a main cylinder communicating with an exhaust passage, a main piston, a supplemental cylinder carried by 105 said main piston and communicating with said main cylinder and with a source of fluid supply, a supplemental piston mounted in said supplemental cylinder, and a sleeve coöperating with said supplemental piston to control the communication between said supplemental 110 cylinder and said source of supply.

5. In an engine, a main cylinder communicating with an exhaust passage, a main piston, a supplemental cylinder carried by 115 said main piston, communicating with said main cylinder and having an inlet port, and parts coöperating with each other and with said supplemental cylinder to control said inlet port.

6. In an engine, a main cylinder communicating with an exhaust passage, a main piston, a supplemental cylinder carried by 120 said main piston, communicating with said main cylinder and having an inlet port, and coöperating parts to control said inlet 125 port, said parts being mounted within and without said supplemental cylinder, respectively.

7. In an engine, a main cylinder communicating with an exhaust passage, a main 130

5 piston, a supplemental cylinder carried by said main piston, communicating with said main cylinder and having an inlet port, and coöperating devices to open said inlet port on one stroke of said main piston and to close it on the next stroke of said main piston.

8. In an engine, a main cylinder communicating with an exhaust passage, a main 10 piston, a supplemental cylinder carried by said main piston, communicating with said main cylinder and having an inlet port, and means to open said inlet port as the main piston nears the end of its inward stroke 15 and to close said inlet port at the beginning of the outward stroke of said main piston.

9. In an engine, a main cylinder communicating with an exhaust passage, a main 20 piston, a supplemental cylinder carried by said main piston, communicating with said main cylinder and having an inlet port, a supplemental piston mounted within said supplemental cylinder, and a device coöperating with said supplemental piston to 25 control said inlet port, said supplemental piston being adapted to have its head interposed between said device and said main cylinder to protect said device from the force of explosion in said main cylinder.

30 10. In an engine, a main cylinder communicating with an exhaust passage, a main piston, a supplemental cylinder carried by said main piston, communicating with said main cylinder and having an inlet port, a 35 supplemental piston mounted within said supplemental cylinder and adapted to form a part of the head of the main piston and to receive a portion of the force of the explosion and having movement relatively to 40 said main piston to open and close said inlet port in said supplemental cylinder, a sleeve coöperating with said supplemental piston to control said inlet port, and means for causing said supplemental piston and 45 said sleeve to move with said main piston and to have movement relatively thereto.

11. In an engine, a main cylinder communicating with an exhaust passage, a main 50 piston having an opening in the head thereof, a supplemental cylinder in said opening, having communication with the main cylinder and also having an inlet port communicating with the source of fluid supply, the wall of said supplemental cylinder being 55 spaced away from the inner walls of said main piston, a supplemental piston mounted within said supplemental cylinder, and a sleeve mounted on the exterior of said supplemental cylinder and having a port 60 adapted to be moved into and out of alignment with said inlet port.

12. In an engine, a main cylinder communicating with an exhaust passage and having an inclosed crank case, a main 65 piston mounted within said cylinder compris-

ing a head and a cylindrical extension, a supplemental cylinder in the head of said main piston, communicating with said main cylinder and extending into the hollow extension of said main piston, said supplemental cylinder having an inlet port, a supplemental piston mounted within said supplemental cylinder and having movement relatively thereto to open and close said inlet port, a sleeve mounted on the exterior 70 of said supplemental cylinder and having a port adapted to be moved into and out of alignment with said inlet port, and means for imparting movement to said supplemental piston and said sleeve.

13. In an engine, a main cylinder communicating with an exhaust passage, a main 75 piston having an inlet passage therein communicating with said main cylinder and forming a pocket, means coöperating with said main piston to compress the charge in 80 said pocket, and means for exploding said charge in said pocket.

14. In an engine, a main cylinder communicating with an exhaust passage, a main 90 piston having an inlet passage therein communicating with said main cylinder and forming a pocket, a piston mounted in said passage and coöperating with said main piston to compress the charge in said pocket, 95 and a spark plug mounted in substantial alignment with said pocket.

15. In an engine, a main cylinder communicating with an exhaust passage, a main 100 piston, a supplemental cylinder carried by said main piston and communicating with said main cylinder and with a source of fluid supply, and means coöperating with said main piston to control the communication between said supplemental cylinder and said 105 source of supply and to cause a supplemental compression of the fluid within said supplemental cylinder.

16. In an engine, a main cylinder communicating with an exhaust passage, a main 110 piston, a supplemental cylinder carried by said main piston and communicating with said main cylinder and with a source of fluid supply, and a supplemental piston mounted in said supplemental cylinder, and means to 115 cause said supplemental piston to move forward relatively to said main piston during the compression stroke of said main piston.

17. In an engine, a main cylinder communicating with an exhaust passage, a main 120 piston, a supplemental cylinder carried by said main piston and communicating with said main cylinder and with a source of fluid supply, a supplemental piston mounted in said supplemental cylinder, means to 125 cause said supplemental piston to move forward relatively to said main piston during the compression stroke of said main piston, and a spark plug mounted on the head of said main cylinder and arranged to project 130

- into said supplemental cylinder when said main piston is in its outermost position.
18. In an engine, a main cylinder, a main piston, a supplemental cylinder carried by said main piston and having a port, a supplemental piston mounted in said supplemental cylinder, a crank shaft, connecting rods connecting said main piston and said supplemental piston, respectively, with said crank shaft, and operable means for causing said supplemental piston to have movement relatively to said main piston during the movement of the latter.
19. In an engine, a main cylinder, a main piston, a supplemental cylinder carried by said main piston and having a port, a supplemental piston mounted in said supplemental cylinder, a sleeve mounted on said supplemental cylinder and coöperating with said supplemental piston to control said port, a crank shaft, and devices connecting said main piston, said supplemental piston and said sleeve with said crank shaft to cause said parts to move in unison and to cause said supplemental piston and said sleeve to have movement relatively to said main piston.
20. In an engine, a main cylinder communicating with an exhaust passage, a main piston, a crank shaft, a connecting rod connecting said main piston with said crank shaft, a wrist pin carried by said crank shaft and serving to connect said connecting rod thereto, a supplemental cylinder carried by said main piston, communicating with said main cylinder and with a source of fluid supply, a supplemental piston mounted in said supplemental cylinder, a connecting rod connected with said supplemental piston, an eccentric mounted on said wrist pin, and a strap connecting said last-mentioned connecting rod with said eccentric.
21. In an engine, a main cylinder communicating with an exhaust passage, a main piston, a crank shaft, a connecting rod connecting said main piston with said crank shaft, a supplemental cylinder carried by said main piston and communicating with said main cylinder and with a source of fluid supply, a supplemental piston mounted in said supplemental cylinder, means to move said supplemental piston relatively to said main piston, a sleeve mounted on said supplemental cylinder, a lever mounted on said main piston, a connection between said lever and said sleeve, and a connection between said lever and the connecting rod for said main piston.
22. In an engine, a main cylinder communicating with an exhaust passage, a main piston, a crank shaft, a connecting rod connecting said main piston with said crank shaft, a wrist pin carried by said crank shaft and serving to connect said connecting rod thereto, a supplemental cylinder carried by said main piston, communicating with said main cylinder and with a source of fluid supply, a supplemental piston mounted in said supplemental cylinder, a connecting rod connected with said supplemental piston, an eccentric mounted on said wrist pin, a strap connecting said last-mentioned connecting rod with said eccentric, a sleeve mounted on said supplemental cylinder, a bell crank lever mounted on said main piston, a connecting rod connecting one arm of said bell crank lever with said sleeve, and a link connecting the other arm of said bell crank lever with the connecting rod for said main piston.
23. In an engine, a cylinder, and a piston mounted therein, one of said parts having an exhaust port and one of said parts having an inlet port, said exhaust port being adapted to be open when said piston is at the inner limit of its movement, a crank shaft, a connection between said crank shaft and said piston, and means controlled by the movement of said crank shaft across its central position, when said piston is in its innermost position, to open and close said inlet port.
24. In an engine, a cylinder, and a piston mounted therein, said cylinder having an exhaust port arranged near the inner limit of movement of said piston and adapted to be open when said piston is in its innermost position, said piston having an inlet port, and operable means carried by said piston for opening and closing said port, a crank shaft, a connection between said crank shaft and said piston, and means actuated by the movement of the crank of said shaft transversely to the line of movement of said piston, when the piston is in its innermost position, to actuate said operable means for opening and closing said inlet port, whereby the opening and closing of said port take place while said piston is substantially stationary.

In testimony whereof, I affix my signature in presence of two witnesses.
